Application December 23, 1947, Serial No. 793,394

6 Claims. (Cl. 58—28)

1

The present invention relates generally to electric clocks and more particularly to a clock of the electromagnetic impulse type adapted especially for use in automobiles.

The principal object of the invention is to provide certain improvements in the clock construction disclosed in our copending application Serial No. 604,386, filed July 11, 1945, in which a single electromagnet is provided with poles associated with a timing mechanism including a balance wheel armature which controls and is sustained in oscillation by intermittent energization of the electromagnet, and with further poles associated with a separate driving mechanism including an armature to drive the clock gear train.

In the present clock the balance wheel and associated contact mechanism control the energization of the electromagnet to impart a magnetic impulse to the balance wheel once, and for a short period only, of each complete oscillation, and simultaneously impart a magnetic impulse to the driving armature which operates the clock gear train through a pawl and ratchet arrangement.

One feature of the present invention relates to the construction of the balance wheel and associated parts of the timing mechanism to assure starting of the clock and provide practically constant frequency and amplitude of oscillation of the balance wheel during operation under conditions of varying applied voltage.

Other features involve certain improvements in the contact mechanism associated with the balance wheel armature and in the driving mechanism associated with the separate driving armature.

Many other features including the construction and relative arrangement of the several parts of the present clock will be apparent from or specifically noted in the following description of the embodiment shown in the accompanying drawings.

On the drawings:

Fig. 1 is a bottom plan view of the clock mechanism with the back cover removed.

Fig. 2 is a transverse section taken substantially on line 2—2 of Fig. 1.

Fig. 3 is an enlarged fragmentary section of the driving mechanism taken substantially on line 3—3 of Fig. 1.

Fig. 4 is an enlarged fragmentary section of the contact mechanism taken substantially on line 4—4 of Fig. 1.

Fig. 5 is a diagrammatic view of the balance wheel with the magnet poles and contact mech-

2

anism and the electrical circuit associated therewith.

Fig. 6 is a diagrammatic view with the balance wheel in the position of maximum magnetic attraction.

Fig. 7 is a similar view with the balance wheel in an abnormal position it may assume if the contacts interfere.

Referring now to the drawings, the base plate or frame 10 is provided with spaced pillars on which a bridge 11 is secured by screws 12, and a pivot staff 13 is journaled between a jewelled lower bearing 14 in an offset portion of the frame and a jewelled upper bearing 15 which is adjustably mounted in the bridge 11. The pivot staff 13 is preferably die cast in a hub 16 die cast in the balance wheel 17 which also functions as an armature as will be hereinafter described. A hairspring 18 is secured at its inner end to a collet on the hub 16 and is secured at its outer end to a post on the frame 10 with the outer turn of the hairspring passing through a slot in a regulator arm 19. This arm is connected as shown in Fig. 2 to an operating indicator pointer 20 by a pivot post 21, extending through and rotatable in a plate on frame 10 below the staff 13 to provide for the adjustment of the arm 19 to change the effective length of the hairspring to regulate the period of oscillation of the balance wheel in known manner.

An electrical contact 22 which is preferably of one or more of the metals in the rare metal group is die cast in the hub 16 on the pivot staff and provided with a contact portion projecting radially from the hub. The contact portion may be of any desired section but is preferably elliptical as shown in Fig. 4 with the plane of its major axis angularly inclined with respect to the axis of the hub.

A U-shaped bracket 23 is secured to the frame 10, as shown in Fig. 4, by a screw 24 and insulated from the frame by washers 25 and bushing 26 of insulating material. The screw 24 is threaded through one leg of the U-shaped bracket and an adjusting screw 27 having a lock nut 28 extends through the other leg in abutting alignment with the end of screw 24 for a purpose to be hereinafter described. A terminal 29, spring contact arm 30, and spring damper arms 31 and 32 are secured to the bracket 23 by rivets 33. The contact arm 30 is bent upwardly at an angle at its free end and formed with a laterally offset ear 34 which extends toward the pivot staff 13 and is adapted to be engaged by the contact 22 during oscillation of the balance

wheel. This portion of the arm 30 may be made of one or more of the metals in the rare metal group and is provided on its underside with an insulating plate 35 of some hard wearing material such as fibre paper which can be bonded to the arm by a suitable adhesive.

The bracket 23 is formed of material which is slightly resilient with the legs initially biased toward one another so that the screw 27 can be adjusted to vary the spacing of the legs to adjust the contact arm 30 to position the laterally offset ear 34 of the contact arm in the plane of movement of the contact 22. When the contact arm is properly adjusted, the contact 22 will alternately engage the upper face of the ear 34 and the insulating plate 35 during oscillation of the balance wheel.

The contact arm 30 is made of very light spring material so as to be readily deflected from its normal position as the contact 22 engages and slides over either the upper face of the ear 34 or the insulating plate 35, and will tend to oscillate or vibrate when it is released after such deflection. The arms 31 and 32 of very light spring material are adapted to dampen this oscillation or vibration of the contact arm. They are located at opposite sides of the contact arm and formed at their free ends with V-shaped portions extending toward and arranged to engage the contact arm at spaced points between the ends of this arm. Since the free lengths of these damper arms are different and they do not have the same natural period of oscillation and also differ from the natural period of the contact arm, the contact arm is practically critically damped, and the construction is such as to impose only an extremely low mechanical load on the balance wheel as it oscillates during operation.

The above described contact mechanism is adapted to control the intermittent energization of the winding of an electromagnet, indicated generally at 36, to impart periodic impulses to both the balance wheel and to a clock driving mechanism to be hereinafter described. As shown in Fig. 2 the electromagnet 36 includes a core 37, a pair of pole pieces 38 and 39, and a second pair of pole pieces 40 and 41 which are secured together and to the frame 10 by nuts 42 threaded on the ends of the core.

As shown in Figs. 1 and 2 the pole pieces 38 and 39 are so formed as to locate the pole tips in the plane of the balance wheel 17 at points relatively close to the periphery thereof so that the balance wheel functions as an armature in the magnetic field between the pole tips whenever the electromagnet winding is energized by engagement of the contact 22 with the upper face of the ear 34 on contact arm 30. This contact engagement will occur only during the counterclockwise movement of the balance wheel as viewed in Fig. 1 and for only a relatively short portion of this movement during which the balance wheel receives a magnetic impulse which is sufficient to sustain it in oscillation as will be more fully described hereinafter with reference to the diagrammatic showing in Figs. 5 to 7, inclusive.

Referring now to the driving mechanism for the clock gear train, as shown in Figs. 1 and 3, the pole pieces 40 and 41 extend parallel to one another and terminate in spaced ends adapted to impart periodic impulses to an armature 43 which is pivotally mounted for limited oscillation between the ends of these pole pieces. The

armature 43 consists of a U-shaped member of magnetic material which is die cast on a hub 44 together with a shaft 45 which is pivotally mounted in bearing plates 46 and 47 clamped against the sides of the pole pieces 40 and 41 by retainer plates 48 and 49.

A helical spring 50 having one end secured to an outstanding lug 51 on retainer plate 48 and its other end secured to the armature 43 is adapted to urge the ends of the armature away from the pole pieces 40 and 41. The extent of pivotal movement of the armature is limited by the provision of a slot 52 in the bearing plate 46 to receive the bent end of a spring wire arm 53 which is fixed at its other end to the shaft 45 by a collet 54. The spring wire arm 53 also acts as a buffer to cushion the motion of the armature at both ends of its movement as it is oscillated by being moved in one direction by the spring 50 and in the other direction by magnetic action when the electromagnet is energized by the timing mechanism.

A driving pawl in the form of a hairpin spring or spring wire of U-shape, indicated generally at 55, is secured to the armature 43 to oscillate therewith. As shown in Figure 3, this spring is formed with substantially parallel arms of unequal length connected by several turns or coils to provide the desired spring action. The spring 55 is arranged with these arms extending substantially parallel to the axis of the armature shaft 45 with the shorter arm 56 fixed to the hub 44 by a sheet metal clamping member 57. The member 57 extends around the hub 44 with the ends slightly spaced and extending radially therefrom to receive the spring 55. Adjacent the hub 44 the ends of member 57 may be tightly clamped together and welded, if desired, to secure the member and arm 56 of spring 55 to the hub 44, but the external ends of member 57 are spaced apart sufficiently to permit free radial movement of the larger arm 58 of spring 55.

The free end of arm 58 of spring 55 extends through an opening in bearing plate 47 to engage a ratchet wheel 59 and act as a spring pawl to advance the ratchet wheel during oscillation of the armature 43, and the ratchet wheel is utilized to drive the clock gear train. Although the armature 43 will be oscillated at a practically constant frequency as determined by the periodic energization of the electromagnet by the timing mechanism, it has been found that the rate of acceleration of the armature movement in response to magnetic impulses will vary with variations in the applied voltage. To avoid possible variations in the movement of the clock gear train a constant driving force should be transmitted thereto and the teeth of the ratchet wheel 59 are therefore so arranged that the ratchet wheel will be advanced by the pawl 58 only on the return stroke of the armature under the influence of the spring 50 and the driving force will not be affected by any changes in the strength of the magnetic field between the poles 40 and 41.

The ratchet wheel 59 is secured to a driving worm 60 journaled on a shaft 61 which is pressed into and supported by a post 62 on frame 10. An index or star wheel 63 is also secured to the worm 60 and is engaged by a detent spring 64 to prevent reverse rotation or any movement of the ratchet wheel and driving worm at times other than when these parts are being moved in one direction by the spring pawl 58. As shown in Fig. 1, the detent spring 64 is in the form of a coiled wire spring having one end (not shown) in

abutment with the frame 10 and the other end extended and bent to engage the toothed index wheel 63 with the intermediate coiled portion eccentrically supported on a rotatably adjustable member 65 to thereby provide for a slight peripheral adjustment of the bent end with respect to the index wheel. The member 65 is adapted to be locked in position and secured to the frame post 62 by screw 66.

The driving worm 60 engages a worm gear 61 on shaft 68 mounted on the frame 10 between bearing 69 and an adjustable bearing screw 70, and a worm 71 on shaft 68 meshes with a worm gear 72 which is rotatable on the center shaft 73 and forced by a spring 74 through washer 75 into frictional driving engagement with a collar 76 fixed to the shaft. The center shaft 73 extends through the bridge 11 and is provided with a groove 77 to receive one end of a hairpin type spring 78 which is mounted on the bridge 11 by a pin 79. The other end of the spring 78 is engaged within an opening in bridge 11 and the spring is so formed as to exert both side pressure and an end pull on the shaft 73 to take up any side or end play in the shaft.

The center shaft 73 extends through the frame plate 10 and is provided with the cannon pinion 80 and a hub 81 for the hour wheel 82. The reduction gear train between pinion 80 and wheel 82 is not shown but may be of any conventional form and preferably includes an idler gear and a reset mechanism for manually setting the position of the hands as shown in our above-identified application, Serial No. 604,386. The usual dial plate has been diagrammatically indicated at 83 and it will be understood that the hour hand will be mounted on hub 81 and the minute hand mounted on the end of center shaft 73.

A back cover 84, as shown in Fig. 2, is secured to pillars 85 on the frame 10 by screws 86, and the electrical connections, not shown, may extend through dust tight, insulated openings in this cover. The skirt of the cover 84 fits into a peripheral groove 87 in the frame 10 which may, if desired, be filled with a suitable cement to thereby completely seal the clock operating mechanism in back of the frame 10.

Referring now to the diagrammatic showing in Fig. 5, the electrical circuit includes a storage battery 88 with one terminal connected to ground by the conductor 89 and the other terminal connected by conductor 90 to the electromagnet winding 91 and from this winding by conductor 92 to the contact arm 30. When the balance wheel contact 22 is in engagement with the upper uninsulated face of the ear 34 on arm 30, as shown in Fig. 5, the energizing circuit for the winding 91 will be completed through the hub 16 and hairspring 18 to ground 93. The electromagnet is provided with a second winding 94 in bifilar relationship with the winding 91 with this winding 94 short-circuited upon itself by the conductor 95 so as to function as a damping winding to reduce the induced voltages and practically eliminate all sparking at the contact 22 and ear 34 during operation.

The damping winding 94 is tapped at 96 and connected by conductor 97 to an arm 98 of a starting switch which may be manually operated to engage a disk 99 with arm 98 to connect this arm by conductor 100 to the conductor 89, and complete an energizing circuit from the battery to winding 94 through conductor 90. The tap 96 is placed off center on the winding 94 to obtain a differential between the two sections of

that winding. The starting switch may be of any desired form but is shown as associated with the reset stem 101 of a setting mechanism for the clock such as is disclosed in our copending application Serial No. 604,386 so that the starting circuit will be closed whenever the reset stem is being operated to set the clock hands.

In Fig. 5, the location of the balance wheel 17 with respect to the poles 38 and 39 is shown as 10 the normal position of rest or equilibrium to which the balance wheel is urged by the hairspring with the contact 22 resting upon the upper 15 face of the ear 34 of contact arm 30. When the battery circuit is closed with the parts in this position, the winding 91 will be energized to create a magnetic field through the poles 38 and 39 to attract the balance wheel and rotate it in the counter-clockwise direction. The rim of the balance wheel is formed with cam-shaped lobes 102, 103 and 104 to provide a gradually increasing 20 acceleration during normal operation as the balance wheel moves counter-clockwise and shortens the air gaps between the lobe 102 and pole 38 and the lobe 103 and pole 39.

25 After the balance wheel has moved counter-clockwise through a predetermined arc, the contact 22 leaves the ear 34 and the electromagnet and poles will be deenergized but the balance wheel continues to rotate in this direction until 30 its moment balances that of the hairspring which then releases its energy to reverse the direction of rotation of the balance wheel. On the return 35 clockwise stroke the energizing circuit will not be closed as the contact 22 passes the ear 34 since it moves under the ear in engagement with the 40 insulating plate 35. It will be understood that the balance wheel moves clockwise until its direction is again reversed by the hairspring and that thereafter the balance wheel will be sustained in oscillation by the hairspring and periodic magnetic impulses imparted thereto during a relatively small portion of the counter-clockwise movement.

45 In the foregoing description of the automatic starting operation from the position shown in Fig. 5, it was assumed that the contact 22 would be in engagement with the upper uninsulated face of ear 34. Although this may be considered to be the normal stopping position, the balance wheel 50 may stop its oscillation in such a position that the contact 22 is either in engagement with the insulating plate 35 or even slightly spaced from this plate on the under side of the ear 34. In this 55 event the circuit for the winding 91 would not be closed and the clock would not start until the starting switch is manually closed to complete the circuit for energizing the winding 94.

When the winding 94 is energized by closure 60 of the starting switch the magnetic field through the poles 38 and 39 will rotate the balance wheel in a counter-clockwise direction to the position shown in Fig. 6 and tension the hairspring. The balance wheel will then be magnetically held in this position of maximum magnetic attraction 65 until the starting switch is opened whereupon the winding 94 will be deenergized and the hairspring will swing the balance wheel in a clockwise direction and normal operation will be resumed. If the starting switch is associated with the reset stem 101, the switch is so arranged as to be closed when the stem is pulled out to engage the reset gears and will be opened by the return of the stem to normal position after it has been rotated to set the clock hands.

70 Referring now to Fig. 7, the balance wheel has

been shown in an abnormal position which it may assume on very rare occasions, when stopped, in which the contact 22 is abutting the edge of the ear 34 or insulating plate 35 on contact arm 30. This interference prevents the balance wheel from moving in a counter-clockwise direction to be started in accordance with the above described operations. To facilitate the starting of the clock under this unusual condition, the rim of the balance wheel is provided with spaced outstanding ears 105, 106 and 107 which are so located and dimensioned that when the electromagnet is energized the balance wheel will be moved in a clockwise direction to move the contact 22 away from the ear 34 and relieve the interference. It will be seen from Fig. 7 that in this position the magnetic pull on the ears 105 and 106 by the poles 38 and 39, respectively, when the poles are energized, will cause a greater rotative effect than the pull on the lobes 102 and 103, respectively, to thereby move the balance wheel in a clockwise direction. Since the hairspring is tensioned by this clockwise movement, it will swing the balance wheel in a counter-clockwise direction as soon as the electromagnet is deenergized and normal operation will be resumed.

In the preceding description of the operation of the balance wheel there has been no reference to any function for the lobe 104 or the ear 107 on the rim of the balance wheel and it should perhaps be noted that they are never in a position to be attracted by the poles when the electromagnet is energized but are provided so that the balance wheel will be symmetrical and can be properly balanced.

It has heretofore been mentioned that the balance wheel is shown in Fig. 6 in a position of maximum magnetic attraction but it will be noted that the contact 22 is not in engagement with the ear 34 in this position of the balance wheel. When the balance wheel is swinging counter-clockwise during normal operation the magnetic flux in the electromagnet and poles does not stop abruptly as soon as the contact 22 leaves the ear 34 to break the energizing circuit due to the time lag of the circuit. In the position shown in Fig. 6 the magnetic flux has not quite died down and the balance wheel continues to rotate counter-clockwise. As it does this it will be seen that the air gaps between the lobe 102 and pole 38 and the lobe 103 and pole 39 will begin to increase and due to the shape of the ends of the lobes there will be a retarding pull from the poles until the flux has completely died down. This action tends to control the amplitude of oscillation of the balance wheel under conditions of widely varying applied voltage such as occur in automotive applications due to variations in temperature and rate of charge and other conditions affecting the condition of the storage battery.

To also compensate for wide variations in battery voltage the electromagnet core 37, poles 38 and 39, and the balance wheel 17 are preferably made from a high permeability magnetic alloy such as nickel steel which becomes magnetically saturated at relatively low applied magnetomotive forces, so that the magnetic circuit for the timing mechanism is saturated at low applied voltages and an increase in voltage will not affect the magnetic pull on the balance wheel sufficiently to change the balance wheel timing to any appreciable extent.

It will be understood that many modifications in the details of construction as disclosed herein and the separate use of certain features are con-

templated as coming within the scope of the present invention as defined in the claims appended hereto.

We claim:

- 5 1. In an electric clock of the magnetic impulse type, an electromagnet, a pair of poles, a balance wheel of magnetic material mounted for oscillation between said poles, a circuit to periodically energize said electromagnet including coating contact members controlled by the motion of said balance wheel and adapted to close said circuit during a portion of the movement of said balance wheel in one direction, lobes on the rim of said balance wheel adapted to cooperate with said poles when said electromagnet is energized to sustain said balance wheel in oscillation, a starting circuit to energize said electromagnet, a manual switch in said starting circuit, and projecting ears on the rim of said balance wheel adapted to be attracted by said poles when said starting circuit is closed to impart a starting movement to said balance wheel.
- 10 2. In an electric clock having an electromagnet and timing mechanism for periodically energizing said electromagnet, a clock gear train including a ratchet wheel, and a driving mechanism for said ratchet wheel including a pair of poles on said electromagnet, bearing plates secured to said poles, an armature having a shaft pivotally mounted in said bearing plates, said armature being positioned between said poles and adapted to be moved in one direction upon energization of said electromagnet with spring means to move said armature in the opposite direction when said electromagnet is deenergized, a spring arm having one end secured to said armature shaft with the free end of said arm engaging within a slot in one of said bearing plates to resiliently retard and limit the movement of said armature in both directions, and a spring pawl carried by said armature engaging said ratchet wheel for driving said clock gear train responsive to periodic energization of said electromagnet.
- 15 3. In an electric clock, a frame, an electromagnet, a pair of poles, a balance wheel of magnetic material arranged for oscillation between said poles, a circuit for said electromagnet and means to periodically close said circuit to impart a magnetic impulse to said balance wheel including a contact adapted to oscillate with said balance wheel, a spring contact arm engageable intermittently by said oscillating contact, a U-shaped bracket having one leg secured to said frame, means to secure one end of said contact arm to the other leg of said bracket with the free end of said arm extending toward said oscillating contact, means to adjust the spacing of said bracket legs to position the free end of said contact arm in the path of movement of said contact, and auxiliary spring means fixed to said other leg of said bracket extending therefrom into engagement with said contact arm at spaced positions therealong preventing excessive vibration of said spring contact arm subsequent to each disengagement by said oscillating contact.
- 20 4. In an electric clock of the magnetic impulse type, an electromagnet, a pair of spaced poles, a generally circular spoked balance wheel of magnetic material mounted for oscillation between said poles, a circuit periodically energizing said electromagnet including contact elements closed responsive to motion of said balance wheel during a predetermined movement thereof in one direction, the said circuit imparting a magnetic impulse to said balance wheel when

closed, said balance wheel rim including circumferentially spaced lobes thereon of gradually increasing radii and formed to provide a shoulder at the trailing end of said lobes when said balance wheel is moved in said one direction, the lobe portions of said balance wheel rim moving past said poles responsive to the inertia of movement of said balance wheel in said one direction beyond said predetermined angular displacement of said balance wheel, that portion of the magnetic flux remaining temporarily within the poles after the opening of the electromagnetic circuit by said contacts acting on the passing shoulders of said lobes providing a magnetic retarding effect on movement of said balance wheel in said one direction after the said predetermined movement thereof.

5. In an electric clock of the magnetic impulse type, an electromagnet, a pair of spaced poles, a balance wheel of magnetic material having a generally circular rim including spaced lobes thereon of gradually increasing radius and formed to provide a shoulder at one end thereof, said balance wheel being mounted for oscillation between said poles, a circuit periodically energizing said electromagnet, coacting contact members controlled by the motion of said balance wheel closing said circuit during a predetermined angular displacement of said balance wheel in one direction imparting a magnetic impulse to 30 said balance wheel when said circuit is closed, the lobe portions of the balance wheel rim moving past said poles responsive to the movement inertia of said balance wheel in said one direction beyond said predetermined angular dis- 35

placement thereof, the movement of said lobes past said poles presenting the shoulders of said lobes beyond the poles whereby to receive from said poles a magnetic retarding effect on continued movement of said balance wheel in said one direction by that portion of the magnetic flux remaining within the poles after opening of the electromagnet circuit by said contacts.

10 6. An electric clock of the impulse type as claimed in claim 5 wherein the poles of the electromagnet are provided with narrow ends facing the rim of said balance wheel spaced less than 180 degrees relative thereto.

PETER R. CONTANT.
